(57) **CLAIM**

The ornamental design for an “ice chest with wheels,” as shown and described.

DESCRIPTION

FIG. 1 is a perspective view of an ice chest with wheels from the front, right and above, showing my new design;

FIG. 2 is a front side elevation view thereof;

FIG. 3 is a rear side elevation view thereof;

FIG. 4 is a right side elevation view, the left side elevation being the mirror image thereof;

FIG. 5 is a top plan view thereof; and,

FIG. 6 is a perspective view thereof from the rear, right and below.
